UNITED STATES PATENT OFFICE.

RICARDO DOCAMPO, OF BUENOS AIRES, ARGENTINA.

MOUTHPIECE FOR SMOKING TOBACCO.

Application filed April 6, 1918. Serial No. 227,110.

To all whom it may concern:

Be it known that I, RICARDO DOCAMPO, a subject of the King of Spain, a merchant, residing at Calle Maipu 671, Buenos Aires, Argentina, have invented an Improvement in a Mouthpiece for Smoking Tobacco, of which the following description, in connection with the accompanying drawings, is a specification, like characters on the drawings representing like parts.

This invention relates to a novel system of mouth-piece for smoking cut or relatively finely divided tobacco, such as used in pipes or cigarettes, for example an essential feature of which consists in the particular arrangement of the tobacco and in the provision of means for gradually pushing or conveying the same to the place of its combustion. Owing to this arrangement, no smoke will be allowed to pass through the column of tobacco, thereby drying and saturating the same with nicotine, as is the case in connection with common mouth-pieces and tobacco pipes. In consequence, the strength and aromatic qualities of the tobacco will not be impaired at any time while the charge is being consumed. Preferably also the smoke will be conducted from the burning tobacco to the mouth piece through a separate passage.

With a mouth-piece according to my invention, only tobacco is smoked, that is, without the strip of paper which actually envelopes the cigarettes and which so much prejudices the health of smokers.

To the above important advantages and those inherent to the uniform combustion and the preservation of the strength and aromatic qualities of the charge, is to be added the saving realized by the fact that this device allows of consuming the entire charge of tobacco introduced thereinto.

My said mouth-piece substantially consists of a cylindrical body, provided with an elongated duct or opening into which the tobacco is filled and within which moves a small disc, operated by a spring which gradually pushes the tobacco towards the point of its combustion as this latter is progressing.

For the purpose of a clear understanding of this invention, detailed illustrative draw-

ings have been annexed to this specification, in which:—

Figure 1 shows a mouth-piece or tube 55 constructed in accordance with the invention, being partially charged with tobacco.

Figure 2 represents a central longitudinal section of the same, and

Figure 3 is a section along the line A—B 60 of Figure 1.

In said drawings, 1 indicates the tubular body at the end of which is formed a small enlargement 2 which forms the space of combustion and at the bottom of which has been 65 provided an orifice which corresponds with the suction tube 3, whose opposite orifice is situated at the centre of the end which constitutes the mouth-piece proper and which for that purpose has been suitably recessed and 70 shaped for its better adaption. Said body 1 is provided with an elongated opening or duct within which moves a pusher herein a small disc 4, secured to the ring 5 and operated by a spring 6. For the purpose of 75 facilitating the operation of filling, a slot 7 has been formed at the end of said elongated duct which allows of retaining the disk while filling in the tobacco, said retention being obtained by slightly turning the 80 ring 5 so as to cause the disc to engage with the slot.

The operation is as follows:—

The pusher disk may be retained in its position of maximum retraction, to facilitate loading the device, by turning the said ring 5 into engagement with the retaining slot 7. Then, the tobacco is introduced, either cut in form of threads or relatively finely divided particles, so as to fill all the 85 space between the elongated opening and the enlarged end or place of combustion. Thereupon, the pusher disc is released and the tobacco is lit, at a point corresponding to the enlarged end of the mouth-piece. In 90 this way, the suction exerted through the tube or passage 3, acts upon the tobacco charge at the forward end of the smoking tube or mouth-piece, and will maintain combustion at said enlarged end and the tobacco 95 will be conveyed or pushed towards said point as its consumption progresses, owing to the action of the pusher plate 4 which, as before stated, is operated by the spring 6. 100

By this means, the column of tobacco is gradually pushed towards the place of combustion without being heated or traversed by the smoke, such as is the case with the ordinary mouth-pieces, since the smoke passes by the tube 3 from the point of combustion directly and only to the smoker's mouth. It will also be noted that the smoke does not pass through the disk 4, nor through the chamber containing the spring 6, thus avoiding the deposit upon said spring or disk, or within said chamber, of any products of combustion due to cooling or otherwise, which might impair the proper functioning of said disk or spring and would necessitate cleaning of said parts in order to secure their proper operation and to keep the smoking tube sweet.

It will be understood that the form of construction of the mouth-piece shown in the drawings, merely is to be considered by way of example, as without changing the system, the mouth-piece may be provided with several dismountable parts, for allowing of the same to be readily cleaned, and also its form or outer design may be modified in many ways.

Having now particularly described and ascertained the nature of my said invention and in what manner the same is to be performed, I declare that what I claim is:—

1. A device of the class described comprising in combination, a mouth piece, a reservoir closed at both ends and having a supply opening extending substantially the length thereof for replenishing the supply of tobacco, a portion of said reservoir constituting a combustion area, means for progressively moving the tobacco in said reservoir toward and into said combustion area, and a passage providing communication

only between said combustion area and said mouth piece for conducting smoke to the mouth piece without contacting with the reserve supply of tobacco in said reservoir. 45

2. In a device of the class described, in combination, an elongated reservoir to receive a supply of tobacco and including a combustion area adjacent one of its ends, a pusher arranged for movement in said reservoir toward said combustion area, spring means tending to move said pusher toward said combustion area, means including a slot adapted to permit the turning of said pusher to effect the retention thereof in its retracted position during the filling of the reservoir, and a suction passage providing communication directly and only between said mouth-piece and said combustion area. 55

3. In a device of the class described, in combination, a tubular tobacco container closed at both ends and having a lateral opening for replenishing the supply of tobacco, a mouth piece at one end of said tubular container, a passage communicating with said mouth-piece and the opposite end of said tubular container, means including a disk arranged within said tubular container for progressively moving the tobacco therein against the end of said container with which said passage communicates, and a ring connected with said disk through said lateral opening, adapted partially to surround said reservoir and constitute positioning and guiding means for said disk. 70 75

In testimony whereof, I have signed my name to this specification.

RICARDO DOCAMPO.
